UNITED STATES PATENT OFFICE.

WILLIAM H. ROSE, OF JERSEY CITY, NEW JERSEY.

WINDOW VENTILATOR.

Application filed November 26, 1926. Serial No. 150,771.

The device of my invention relates to ventilators and refers particularly to ventilating deflectors for window use.

One of the objects of my invention is a ventilator in which the deflector element is readily attached to, and removed from the supporting side pieces.

Another object of my invention is a ventilator free from noise and rattle incident to air impact.

Another object of my invention is a ventilator made of inexpensive material.

Another object of my invention is a knock-down ventilator which can be easily assembled and easily set up.

In the accompanying drawings illustrating modified forms of the device of my invention, similar parts are designated by similar numerals.

Figure 1 is a front view of one form of my device positioned within a window frame.

Figure 2 is a cross-section through the line 2—2 of Figure 1.

Figure 3 is a cross-section through the line 3—3 of Figure 2.

Figure 4 is a perspective view of a holding member.

Figure 5 is a perspective view of a deflector.

Figure 6 is a fragmentary vertical cross-section of a modified form of deflector.

The particular form of the device of my invention shown in the accompanying drawings comprises a corrugated cardboard deflector, having the central member 10 and the two angularly positioned truncated triangular end pieces 11, 11, the end pieces being formed by scoring the cardboard and bending upon the score lines. Each deflector end 11 has a plurality of recesses, or slots, 12, 12 entering from its outer edge. The upper edge of the deflector is covered by a protecting paper or textile member 13.

A U-shaped resilient metallic holding member 14, has one of its edges 15 bent inwardly and has a plurality of holes 16, 16, positioned in the two sides of the holding member in alignment with each other, and also positioned in alignment with the slots 12, 12 of a deflector end 11, when the end 11 is positioned within the holding member.

A thumb screw 17 is capable of placement through aligned holes 16, 16 and a slot 12.

The operation of my device is as follows: holding members 14, 14 are placed upon

the lower portions of the inner faces of opposite sides of a window frame 18, with the opening inwardly toward the room, and a thumb-screw 16 passed through each pair 60 of holes 16 and screwed into the window frame 18, thus fixedly attaching the holding members to the frame.

The two deflector ends 11, 11 are then passed inwardly of the two holders, the screws 16, 16 entering the slots 12, 12. The resiliency of the holders 14, 14 will cause their edges 15, 15 to grip and hold the deflector ends, or this gripping effect can be increased, if desired, by screwing the thumb 70 screws slightly inwardly.

The holding members may be devoid of the turned edges if desired, contact being maintained between the holding members and the deflector ends by pressure caused by the thumb screw, or both edges may be turned inwardly.

In this manner, the deflector will be held rigidly in place, but can be readily removed if desired.

In the modification shown in Figure 6, a stiffening rod 19 is placed along the upper edge of the deflector central portion 10 and below the covering, or binding, 13.

It will be noted that as the holding members are fixedly attached to the window frame and as the deflector is non-metallic, there can be no rattling effect.

Further, it will be noted that as the deflector is of a yielding material, the edge 15 of the holding member will readily set itself into the deflector to maintain it in position.

By "cardboard", I mean both ordinary cardboard and corrugated cardboard and other similar materials may be employed and the device may be painted and water-proofed.

I do not limit myself to the particular size, shape, number, arrangement or material of parts as shown and described, as these are given simply as a means of clearly describing my invention.

What I claim is:—

1. In a window ventilator, in combination, a stiff deflector of yieldable material, having angularly positioned end members, said end members having a plurality of slots therein; two U-shaped metallic holding members, each capable of receiving a deflector end, said holding members having a plurality of series of holes in alignment with each other and in alignment with the slots

of the inserted deflector ends; and means passing through the holes capable of affixing them to opposite window frames.

6. 2. In a window ventilator, in combination, a stiff deflector of cardboard, having angularly positioned end members, said end members having a plurality of slots therein; two U-shaped metallic holding members each capable of receiving a deflector end, the holding members having a plurality of series of holes in alignment with each other and in alignment with the slots of the inserted deflector ends; and screw means passing through the holes capable of affixing them to opposite window frames.
10. 3. In a window ventilator, in combination, a stiff deflector of yieldable material, having angularly positioned end members, said end members having a plurality of slots therein; two U-shaped metallic holding members having an inturned gripping edge, each capable of receiving a deflector end, the holding members having a plurality of series of holes in alignment with each other and in alignment with the slots of the inserted deflector ends; and means passing through the holes capable of affixing the holding members to opposite window frames, and a stiffening member carried by the deflector.
15. 4. In a window ventilator, in combination, a cardboard deflector having angularly positioned end members, said end members having a plurality of slots therein; two U-shaped metallic holding members having an inturned gripping edge, each capable of receiving a deflector end, the holding members having a plurality of series of holes in alignment with each other and in alignment with the slots of the inserted deflector ends, means passing through the holes capable of affixing the holding members to opposite window frames, and a stiffening member carried by the deflector.

5. In a window ventilator, in combination, a cardboard deflector having angularly positioned end members, said end members having a plurality of slots therein; two U-shaped metallic holding members having an inturned gripping edge, each capable of receiving a deflector end, the holding members having a plurality of series of holes in alignment with each other and in alignment with the slots of the inserted deflector ends, means passing through the holes capable of affixing the holding members to opposite window frames, and a stiffening member carried by the deflector.

Signed at New York city, in the county of New York and State of New York, this 23rd day of November, 1926.

WILLIAM H. ROSE.
